DISPOSABLE SANITARY COVER FOR TELEPHONE HANDSETS

Willie L. Velasquez, 311 Effie, Fresno, Calif. 93701

Filed July 12, 1968, Ser. No. 12,735

Term of patent 14 years

Int. Cl. D14—03

U.S. Cl. D26—14

FIG. 1 is a perspective view of a disposable sanitary cover for telephone handsets, showing my new design.

FIG. 2 is a bottom plan view of my new design.

FIG. 3 is a top plan view thereof.

FIG. 4 is a side elevation of one side thereof.

FIG. 5 is a side elevation of the side opposite to that shown in FIG. 4.

FIG. 6 is an end elevation thereof with the opposite end being substantially identical to the end shown.

The broken lines are shown for illustrative purposes only.

I claim:

A disposable sanitary cover for telephone handsets, substantially as shown and described.
